(57) **CLAIM**

The ornamental design for a radially compressible guitar pick, as shown and described.

DESCRIPTION

FIG. 1 is a side perspective view of a radially compressible guitar pick showing my new design;

FIG. 2 is an alternate side perspective view thereof; and,
FIG. 3 is a front elevational view thereof.

The broken line showing a fragmentary hand in FIG. 2 is for illustrative purposes only and forms no part of the claimed design.
